UNITED STATES PATENT OFFICE

JAMES MILLARD ROYAL, OF VILLA PARK, ILLINOIS, ASSIGNOR TO WESTERN ELECTRIC COMPANY, INCORPORATED, OF NEW YORK, N. Y., A CORPORATION OF NEW YORK

METHOD OF AND APPARATUS FOR COVERING CORES

Application filed September 10, 1927. Serial No. 218,840.

This invention relates to a method of and an apparatus for covering cores, and more particularly to a method of and apparatus for applying an insulating covering to an electrical conductor.

Objects of the invention are to provide a method and apparatus by which fibers may be applied directly to a core without spinning them into a yarn.

10 The invention contemplates the provision of a method and apparatus in which a roving of cotton is separated into its individual fibers which are deposited in a column of air to carry them to the core to which they are to be applied where a rotating movement is imparted to the fibers, wrapping them about the core, after which the fibers are polished on the core to give the covering a neat and finished appearance.

20 It is believed that a complete understanding of the invention may be had by reference to the following description taken in conjunction with the accompanying drawings, in which

25 Fig. 1 is a longitudinal sectional view of one embodiment of the invention in an apparatus which may be employed in practicing the method;

Fig. 2 is a cross sectional view taken on line 2—2 of Fig. 1;

Fig. 3 is a cross sectional view taken on line 3—3 of Fig. 1;

Fig. 4 is a longitudinal sectional view of a modified form of an apparatus embodying the invention;

Fig. 5 is a cross sectional view taken on line 5—5 of Fig. 4, and

Fig. 6 is a cross sectional view taken on line 6—6 of Fig. 4.

40 Referring to the drawings in which the same reference characters indicate similar parts in the several views and especially to Figs. 1, 2 and 3 which illustrate one embodiment of the invention, a frame 11 of any suitable design is shown supporting a roller bearing 12 by means of which a housing for a fiber applying and polishing portion of the apparatus is rotatably mounted. A conduit 15 for feeding the insulating material to the applying and polishing mechanism is supported in

the upper portion of the frame 11 and extends into close proximity to the applying mechanism. The applying mechanism may be driven through a gear 10 from any suitable source of power (not shown). A current of air is maintained through the conduit by means of a centrifugal fan 16 provided with radial blades 17. The end of the conduit terminates in a collector grate 18 which serves to concentrate the fibers and is provided with a plurality of slots 19 through which a large portion of the air passes radially into an annular chamber 21 so that the velocity of the air in a collector chamber 22 is greatly reduced as it passes downward into a spherical polisher chamber 23 and tubular openings 24 where it combines with the air coming down in the annular chamber 21 and is exhausted by the fan 16.

55 The fibrous material, such as cotton, wool or asbestos fibers, which is to form the insulating covering about the conductor 60 is fed into the conduit in the form of a roving or sliver and passes between feed rollers 26 driven by any suitable source of power, the speed 60 of which determines the amount of material used by the apparatus and, therefore, the thickness of the layer of insulation. From the feed rollers 26 the material passes into a carding or separating mechanism 27 which 65 consists of a perforated drum provided on its cylindrical surface with a plurality of radially projecting pins which serve to separate the roving or sliver into its individual fibers and the current of air passing through the perforations in the drum at the exit side of the drum chamber serves to remove the fibers 70 from the drum and carry them into the collector grate 18. In the collector grate 18 a large portion of the air is permitted to escape radially through the slots 19 and the fibers moving at a considerably retarded velocity drop into the collector chamber 22 where they are given a rotary movement by the rotation of the collector chamber. The 75 rotation of the fibers in the collector chamber causes them to be wrapped about the conductor and upon a downward movement of the conductor caused by any suitable advancing mechanism (not shown) the wrapped 80

85 fibers are polished by the action of the rotating collector chamber 22 and the fiber applying mechanism 12. The fiber applying mechanism 12 is supported in the frame 11 and is driven by a gear 10 from the fan 16. The fiber applying mechanism 12 consists of a fiber applying drum 13 which is supported by a fiber applying roller 14. The fiber applying drum 13 is provided with a plurality of 90 slots 15 through which air passes radially into an annular chamber 16 so that the velocity of the air in a fiber applying chamber 17 is greatly reduced as it passes downward into a fiber applying 95 chamber 18 and tubular openings 19 where it combines with the air coming down in the annular chamber 16 and is exhausted by the fan 16. The fiber applying drum 13 is provided with a plurality of 100 slots 20 through which air passes radially into an annular chamber 21 so that the velocity of the air in a fiber applying chamber 22 is greatly reduced as it passes downward into a fiber applying chamber 23 and tubular openings 24 where it combines with the air coming down in the annular chamber 21 and is exhausted by the fan 16.

fibers pass into the polishing chamber 28 which is provided with two resilient polishing blades 28 which polish the fibers on the conductor, giving the insulation a neat and finished appearance.

5 A modified form of an apparatus embodying the invention is shown in Figs. 4, 5 and 6 in which the material is fed into the conduit 15 and is passed between the feed rollers 10 26 from whence it is carried by the air current into a receiving cup 31. At the entrance to the receiving cup a plurality of pins 32 are provided which tend to separate the roving or sliver into its individual fibers. Ad- 15 jacent the pins 32 in the receiving cup are a plurality of apertures 33 through which a current of air is passed upon each revolution of the receiving cup as it passes a slot 34 in the flared portion of the conduit extending over 20 the cup. The current of air is a result of the low pressure in the receiving cup due to the centrifugal fan 16 and serves to remove the fibers from the fingers 32. A current of air in the receiving cup entering through the con- 25 duct carries the material into an annular channel 41 provided in the receiving cup from whence the fibers are carried by the air current around an applicator finger 42, the front face of which contacts with the conductor 30 60 and is provided with a plurality of grooves 43 so as not to make continuous contact with the conductor throughout its length. A polisher 44 is pivotally mounted on a pin 45 and is urged lightly toward the conductor by 35 a spring 46 until the apparatus attains its normal speed when the proper force will be applied to the polisher by the action of centrifugal force. The air entering the annular passage 41 escapes through the slots 43 giv- 40 ing the applicator and polisher an opportunity to apply the fibers to the conductor while the air passes through the passage 51 and is exhausted by the fan 16. Access may be had to the chamber housing the applicator and 45 48 the polisher by withdrawing the pin 45 and removing the polisher for the purpose of cleaning the apparatus.

The invention makes it possible to use a low grade of material which it would be difficult to spin into a yarn of uniform quality and strength and at the same time obviates the necessity of spinning the fibers into a 50 yarn and produces a high grade of insulation.

55 It will be understood that the invention herein described and illustrated is merely a useful and convenient form of the invention which is capable of many other modifications without departing from the spirit and scope 60 of the invention.

What is claimed is:

1. In an apparatus for applying a fibrous covering to a core, means for producing a current of air to convey the fibrous material to 65 the core, a collector grate for concentrating

the fibers and exhausting a portion of the air, and means for wrapping the fibers about the core.

2. In an apparatus for applying a fibrous covering to a core, means for producing a current of air to convey the fibrous material to the core, a collector grate having a plurality of slots for concentrating the fibers and exhausting a portion of the air, and means for wrapping the fibers about the core. 70

3. In an apparatus for applying a fibrous covering to a core, means for feeding a roving of cotton at a predetermined rate to obtain a given thickness of covering, means for separating the roving into individual fibers, 80 means for producing an air current to convey the fibers to the core, a collector grate to collect the fibers and exhaust a portion of the air current, and means for revolving the fibers to apply the fibers to the core. 85

4. In an apparatus for covering cores with fibrous material, an air exhausting means through which a core may be advanced, a conduit connected therewith for surrounding the core and through which air is exhausted by the first mentioned means for conveying separated fibers of material to the core, a terminal member for the conduit having a slotted wall for decreasing the velocity of the air, collecting the fibers and depositing them upon the core, and means associated with the exhausting means for revolving the deposited fibers about the axis of and thereby wrapping them around the core. 90

5. In an apparatus for covering cores with a fibrous material, a rotatable housing, an exhaust fan therein and rotatable therewith, a fixed conduit terminating at the housing adjacent the intake side of the fan, and means for rotating the housing to cause fibers to be 100 conveyed to the core by air exhausted through the conduit and to be wrapped around a core passing through a portion of the conduit and the housing. 105

6. In an apparatus for covering cores with a fibrous material, a rotatable housing, an exhaust fan therein and rotatable therewith, a fixed conduit terminating at the housing, a tapered extension thereof projecting within the housing, a tubular member within the 110 housing and rotatable therewith having an outwardly flared end surrounding the tapered extension of the conduit, means for delivering fibers to the conduit, and means for rotating the housing and the exhaust fan to 115 cause the fibers to be carried through the conduit in an air column and the extension thereof, and to wrap them by means of the tubular member around a core passing through a portion of the conduit, and through the extension, the tubular member and the fan. 120

7. In an apparatus for covering cores with fibrous material, a rotatable housing, a fan carried by said housing and rotatable therewith, a tubular member disposed in said hous- 125

ing and in communication with the intake side of said fan, a conduit disposed in communication with said housing, and said tubular member, and means for rotating said housing and said fan to cause a column of air to pass through said conduit and said tubular member.

8. In an apparatus for covering cores with fibrous material, a rotatable housing, a fan carried by said housing and rotatable therewith, a tubular member disclosed in communication with the intake side of said fan, a conduit disposed in communication with said housing and said tubular member, means for 10 rotating said housing and said fan to cause a column of air to pass through said conduit and said tubular member, and means for delivering fibers to the conduit to be carried by the column of air into said tubular member 15 and be wrapped around a core passing through a portion of said conduit, and said 20 tubular member.

9. In an apparatus for covering cores with fibrous material, a rotatable housing, a fan carried by said housing and rotatable therewith, a tubular member disposed in said housing and in communication with the intake side of said fan, a conduit disposed in communication with said tubular member and having a plurality of slots providing communication with said housing, means for rotating said housing and said fan to cause a column of air to pass through said conduit, and said tubular member, and means for delivering fibers to said conduit to be carried by the column of air into said tubular member and be wrapped around a core passing through a portion of said conduit, and said tubular member.

40 10. In an apparatus for covering cores with fibrous material, a rotatable housing, a fan carried by said housing and rotatable therewith, a tubular member disposed in said housing in communication with the intake
45 side of said fan, a conduit disposed in communication with said tubular member and having a portion extending inwardly toward the axis of said tubular member, means for rotating said housing and said fan to cause a column of air to pass through said conduit, and said tubular member, and means for delivering fibers to said conduit to be carried by the column of air into said tubular member and be wrapped around a core
50 55 passing through a portion of said conduit, and said tubular member.

11. In an apparatus for covering cores with fibrous material, a rotatable housing, a fan carried by said housing and rotatable therewith, a tubular member disposed in communication with the intake side of said fan, a conduit disposed in communication with said housing and said tubular member, means for rotating said housing and said fan to cause a column of air to pass through said

conduit and said tubular member, means for delivering a fibrous material to said conduit, and means disposed in said conduit for separating the fibers from the fibrous material whereby the fibers may be carried by the column of air into said tubular member and be wrapped around a core passing through a portion of said conduit and said tubular member. 70

12. In an apparatus for covering cores with fibrous material, a rotatable housing, a fan carried by said housing and rotatable therewith, a tubular member disposed in communication with the intake side of said fan, a conduit disposed in communication with said housing and said tubular member, means for rotating said housing and said fan to cause a column of air to pass through said conduit and said tubular member, means for delivering a fibrous material to said conduit, means disposed in said conduit for separating the fibers from the fibrous material whereby the fibers may be carried by the column of air into said tubular member and be wrapped around a core passing through a portion of said conduit and said tubular member, said separating means comprising a rotatable member, and radially extending projections carried by said rotatable member for engaging with the fibrous material. 95

In witness whereof, I hereunto subscribe my name this 29 day of August, A. D. 1927.

JAMES MILLARD ROYAL.
